UNITED STATES PATENT OFFICE.

FRANK J. SULLIVAN, OF CLINTONVILLE, WISCONSIN.

COMBINED DRIVING AND STEERING AXLE.

1,272,565.

Specification of Letters Patent.

Patented July 16, 1918.

Application filed May 25, 1916. Serial No. 99,833.

To all whom it may concern:

Be it known that I, FRANK J. SULLIVAN, a citizen of the United States, residing at Clintonville, in the county of Waupaca and 5 State of Wisconsin, have invented certain new and useful Improvements in Combined Driving and Steering Axles, of which the following is a specification.

My invention relates to improvements in 10 a combined driving and steering axle.

The invention aims to provide a combined driving and steering axle, which is exceedingly strong, durable, and may be retained properly lubricated for a prolonged period.

15 A further object of the invention is to provide apparatus of the above mentioned character, so constructed that dust, dirt or the like will be effectively excluded from the interior thereof.

20 A further object of the invention is to provide an axle construction of the above mentioned character, embodying inner and outer cylindrical shells, with ball bearings arranged between the ends of the shells.

25 A further object of the invention is to provide apparatus of the above mentioned character, formed of few and simple parts, which may be readily adjusted, and which may be readily separated and assembled.

30 A further object of the invention is to provide means for maintaining the ball bearings arranged between the relatively movable parts of the apparatus, thoroughly lubricated.

35 Other objects and advantages of the invention will be apparent during the course of the following description.

In the accompanying drawings forming 40 a part of this specification and in which like numerals are employed to designate like parts throughout the same,

Figure 1 is a side elevation of apparatus embodying the invention,

Figure 2 is an end elevation of the same, 45 parts being omitted,

Fig. 3 is a central vertical longitudinal sectional view through the apparatus, and,

Fig. 4 is a transverse sectional view taken on line 4-4 of Fig. 1.

50 In the drawings, wherein for the purpose of illustration is shown a preferred embodiment of my invention, the numeral 5 designates a tubular axle housing or casing which is connected with the running gear of the vehicle or its body. Arranged adjacent each

end of the tubular housing 5 is an inner supporting shell or member 6, which is cylindrical and preferably vertically arranged. The supporting shell or member 6 is provided with a nonrotatable tubular extension or 60 coupling 7, projecting into the housing 5, and fitting snugly therein. The end of the housing 5 is flanged as shown at 8, which flange preferably has its opposite sides cut away so that an opening 16, to be described, 65 will not have to be made over large, to permit of the proper steering of the wheel, and this flange is rigidly attached to the supporting shell or member 6 by means of screws 9. These screws have their head-ends arranged inwardly with respect to the interior of the shell 6 and their outer ends engaged within screw-threaded openings formed in the flanged end 8 of the housing 5. By this arrangement of the screws, the same may be 70 employed larger than could otherwise be done. It is to be understood that any other suitable means may be employed to rigidly secure the inner shell to the housing 5.

Surrounding the inner supporting shell or 80 member 6 is an outer supporting shell or member 10, which is cylindrical and free to turn thereon in a horizontal plane. The outer shell 10 is formed in upper and lower shell-sections 12 and 13, the adjacent ends 85 of which have flanges 14, connected by bolts 15. As clearly shown in Fig. 1, the inner side of the outer shell 10 has an opening 16 formed therein, for receiving the housing 5 during the swinging or shifting of the 90 wheel.

As more clearly shown in Fig. 4, there is an annular space 17, between the inner and outer shells, for receiving lubricant, such as a soft grease. The inner supporting 95 shell or member 6 is provided upon its upper end with an upstanding annular flange 18, receiving therein an annular bearing-ball track or raceway 19. Bearing-balls 20 operate within this track and engage within 100 a co-acting track or raceway 21, carried by an adjustable head or plug 22, having screw-threaded engagement within an opening 23, formed in the upper outer casing section 12, as shown. The head 22 has a preferably 105 centrally arranged screw-threaded opening, receiving a screw-threaded plug 24, adapted to be removed, to permit of the insertion of the lubricant. The bottom of the lower casing section 13 is closed, as shown at 25, and 110

this bottom carries an annular track or raceway 26, receiving bearing-balls 27, engaging a co-acting track or raceway 28 which fits within a flange 28'. The upper and lower ends of the casing sections 12 and 13 are provided with annular grooves 29, receiving packing 30 such as felt, as shown. The upper and lower ends of the inner supporting shell or member 6 is provided with 10 openings 31, leading into spaces or chambers 32. By the employment of co-acting cylindrical inner and outer shells, having horizontal or flat ends, the maximum area is obtained for the ball-bearings, which are preferably of the anti-friction thrust type. Particular attention is called to the fact that the sides of the inner and outer shells do not constitute bearing surfaces, as they are separated by the passage 17, containing a layer 15 or film of lubricant, and all of the load is carried by the ends of the inner and outer shells and their respective ball-bearings. Attention is called to the fact that the ball-bearings may be adjusted by slight turning 20 movement of the head or plug 22, as is obvious.

The outer shell 10 is provided upon its outer side with a flat annular flange or portion 33, shown more clearly in Figs. 1, 2 30 and 3. Adapted to contact with this flange 33 is a co-acting flange 34, formed upon a non-rotatable stub-shaft 35. The flange 34 is provided with a male member or projection 36, extending into an opening 37 35 formed in the outer shell 10. The flange 34 is further provided with an annular flange or rib 38, extending into an annular groove 39 formed in the shell 10. The flanges 34 and 33 are rigidly connected by means of 40 bolts 40 or the like. By the employment of the interfitting portions of these flanges, the strain or load is taken off of the bolts 40, which need only function to hold the parts from separation.

45 The numeral 41 designates a wheel, having a tubular hub 42, which is rotatably mounted upon the stub-shaft 35, with roller bearings 43 arranged therebetween, as shown. There is a dust-guard or ring 44 secured to the inner end of hub 42, for closing such ends, as shown.

Extending through the housing 5 is a driving shaft 45, connected with a driving stub-shaft 46, through the medium of a universal joint 47 of any well known or preferred construction. Suitably connected with the outer end of the driving shaft 46 for rotation therewith is a coupling 48. This coupling 48 is preferably provided with a 55 suitable number of lugs 50, projecting into slots or notches 51, formed in the outer end of the hub 42. The numeral 50 designates a cap, inclosing the coupling 48 and having its inner end contacting with the outer end 60 of the hub 42. This coupling is secured to

the hub by screws 51, extending through openings in members 48 and 50, and having screw-threaded engagement within screw-threaded openings 52 formed in the hub.

As more clearly shown in Fig. 2, a steering crank 51 is rigidly secured to the lower casing section 13, by means of which it may be shifted laterally.

During operation, the interior of the inner shell 6 is preferably retained more or less filled with grease, and the rotation of the universal joint or knuckle 47 serves to force this grease or lubricant outwardly through the openings 31 and into the spaces 32. The grease is thus continuously supplied to the ball-bearings, retaining the same properly lubricated.

It is to be understood that the form of my invention herewith shown and described is to be taken as a preferred example of the same, and that various changes in the shape, size, and arrangement of parts may be resorted to without departing from the spirit of the invention or the scope of the subjoined claims.

Having thus described the invention, I claim:

1. A steering axle; comprising an inner substantially vertical substantially cylindrical shell having upper and lower ends; an outer substantially vertical substantially cylindrical shell surrounding the inner shell and having an interior diameter substantially greater than the exterior diameter of the inner shell so that the sides of the two shells are permanently out of contact, the outer shell being provided with upper and lower ends; pairs of co-acting annular tracks interposed between the adjacent ends of the inner and outer shells and arranged near their peripheries and having oppositely arranged oblique faces; means to rigidly attach the annular tracks with the ends of the inner and outer shells; bearing elements arranged between the co-acting tracks and contacting with the oppositely arranged oblique faces to prevent perceptible lateral and longitudinal movement of one shell with respect to the other; and a wheel rotatably connected with the outer shell.

2. A steering axle; comprising an inner substantially vertical substantially cylindrical shell having upper and lower substantially horizontal ends; the ends being provided with retaining flanges; an outer substantially vertical substantially cylindrical shell receiving the inner shell and having a larger interior diameter than the exterior diameter of the inner shell to provide a permanent space therebetween and having upper and lower substantially horizontal ends, which are in turn provided with retaining flanges; pairs of co-acting annular tracks arranged between the adjacent ends of the inner and outer shells and interfitting with

the retaining flanges to have rigid connection with the shells and located near their peripheries, the co-acting tracks being oppositely arranged; bearing elements arranged between the opposed tracks and contacting with the tracks for preventing perceptible lateral movement of one shell with respect to the other; a spindle attached to the outer shell; a wheel rotatably mounted upon the spindle; and bearing elements between the wheel and spindle.

5 In testimony whereof I affix my signature in presence of two witnesses.

FRANK J. SULLIVAN.

Witnesses:

JULIUS PRENZLOW,
W. H. FINNEY.
